J. J. PRUELL
SASH HOLDER.
FILED OCT. 7, 1920.

Patented Dec. 19, 1922.

1,439,260

UNITED STATES PATENT OFFICE.

JOSEPH J. PRUELL, OF WALPOLE, MASSACHUSETTS.

SASH HOLDER.

Application filed October 7, 1920. Serial No. 415,251.

To all whom it may concern:

Be it known that I, JOSEPH J. PRUELL, a citizen of the United States, residing at Walpole, in the county of Norfolk and State of Massachusetts, have invented certain new and useful Improvements in Sash Holders; and I do declare the following to be a full, clear, and exact description of the invention, such as will enable others skilled in the art to which it appertains to make and use the same.

This invention relates to an improved sash holder or lock, and it has for one of its principal objects, to improve upon the holder disclosed in Patent No. 1,097,108, granted to me on May 19, 1914.

The main difference between the present holder and the patented one resides in a novel and new way of connecting the sash engaging pawl to the stationary attaching member or channel and providing separate and successively operable cam means between the pawl and the channel for effecting longitudinal movement of the latter with respect to the former when the pawl is moved downwardly by the sash when opening the window. Consequently, this action and the difference in operation brings about a new result which insures a more effective frictional grip of the pawl on the sash. It therefore follows that the present holder is a decided improvement upon my patented one and other patented holders with which I am familiar.

Another object of the invention is to provide a holder of the above mentioned type which is simple in construction, being such that after it is once attached to a sash, the locking pawl will effectively engage the sash with which it coacts even if this sash moves slightly further away from the attaching member due to wear, thus overcoming the necessity of removing the device to change its position to accomplish the desired result.

A further object of the invention is to generally improve upon devices of this class by producing one of extreme simplicity, which is highly efficient in use, strong, durable, and exceedingly inexpensive to manufacture.

More specifically speaking, it is an important object of the invention to devise a window lock or holder of this class which embodies the aforesaid pawl and channel-shaped attaching member, the pawl being

connected to the latter in such a way that it is capable of longitudinal movement and there being an abutment carried by the member which constitutes a fulcrum with 60 which the pawl is engaged as it is moved downwardly by the sash which it engages, this fulcrum and inclined cam edge of the pawl which bears thereon, effecting an upward movement of the connecting pin in the 65 inclined slot and the upper walls of the latter serving to bring about the aforesaid longitudinal movement.

Other objects and advantages of the invention will be apparent during the course 70 of the following description.

In the accompanying drawing forming a part of this specification and in which like numerals are employed to designate like parts throughout the same:

Figure 1 is a perspective view of a device constructed in accordance with my invention, showing the manner of positioning the same on a window.

Figure 2 is a side elevation thereof disclosing the normal position of the locking pawl.

Figure 3 is a longitudinal section through the holder disclosing the construction and association of parts more clearly.

Figure 4 is a top plan view thereof.

Figures 5 and 6 are detail perspective views of the main elements of the device disassembled.

In the drawing, wherein the preferred embodiment of my invention is clearly illustrated, the letter F designates a window frame in which a pair of sashes S are slideable.

Referring now to the specific and preferred form of the holder disclosed in the drawings, it will be seen that the numeral 1 designates a substantially channel-shaped base or attaching member which is provided in its bottom with suitable apertures 100 through which fastenings are passed for securing the member to the upper end of one of the vertical pieces of the lower window sash. In placing the member in position it is preferred that it be disposed transversely across the sash in the manner clearly disclosed in the drawing. As before indicated, a locking pawl 2, preferably made from a single metal stamping, and provided with a rounded or cam face 3 for frictional engagement with the upper sash, is connected with the attaching member. The

stamping from which the pawl is formed is such that a pair of oppositely disposed laterally extending base arms 4 are provided and these are disposed between the opposed 5 vertical side walls of the attaching member and are movably connected thereto. It is to be noted that the connection of the pawl with the attaching member is not rigid as is the case with the lock disclosed in the 10 aforesaid patent. It therefore follows that instead of rigidly connecting the pawl with the attaching member, I provide the latter in its side walls with oppositely disposed curved and elongated slots 5, the upper walls 15 of which constitute cams and act in a manner to be hereinafter described. A pivot and connecting pin 6 is detachably connected with the narrow ends of the aforesaid arms 4 and this pin extends through and is 20 movable in said slot. It might be said that such a construction provides a movable fulcrum for the pawl and the slot permits the aforesaid longitudinal movement which is caused by the pin 6 riding against the upper 25 curved walls of the slots. This is one of the cam means hereinbefore referred to. In order to cause the pin 6 to move upwardly in the slot to bring about this cam action, I provide a horizontally disposed pin 7 which 30 is extended through the side walls of the attaching member just below the slots and in advance of these. This pin functions mainly as a fulcrum for the pawl, but is normally ineffective and comes into play 35 when the pawl is moved downwardly by the sash and is brought into engagement therewith. By carefully examining the rear portions of the lower edges of the arms 4, it will be seen that these are inclined as indicated at 10 and these inclined edges form 40 cams which act in advance of the aforesaid cam edges of the slot. While on the description of this fulcrum pin 7, I may point out that if desired, it may be mounted in 45 such a way that it is capable of rotation. By such an arrangement, it will be seen that the engagement of the cam edges 10 of the locking pawl will tend to automatically rotate it and in so doing, the points of contact between the cam edges and pin will be 50 constantly changed and naturally, the life of the pin will be greatly prolonged.

Although the force of gravity would automatically move the latch to operative position, it is desirable in this case, as in my patented case, to move it to operative position by means of a coiled spring 8, this spring surrounding the fulcrum pin and having one of its ends anchored to one of the arms 4 and its opposite end bearing 55 against the abutment pin 7 as better shown in Fig. 3. Employment of this spring will assist in moving the pivot pin in the slot 5. An operating finger-piece will, of course, be 60 provided, this finger-piece being formed in

the same way that it is formed in my patented device, that is, by bending a portion of one of the arms 4 laterally as indicated at 8 and permitting this arm to extend beyond the attaching member for convenient operation. 70

In use, the channel-shaped attaching member is placed transversely across the lower sash in the manner shown in Fig. 1, and fastening screws are passed through apertures in its bottom to secure it rigidly in position. Care should be taken in placing the attaching member in position that it is spaced away from the upper sash just far enough to cause the fulcrum pin of the locking pawl to seat in the lower ends or near the lower ends of the slots 5. This exact positioning of parts is not essential, although it is desirable. The finger-piece 8 may then be pressed downwardly to swing 85 the pawl on its pivot to permit the sash to be easily raised or lowered as the case may be. As soon as the finger is removed from the part 9, the coil spring 8 automatically returns the pawl to operative position, in 90 which position it frictionally engages the upper sash and prevents further movement of either of the sashes. Now, in case an attempt is made to open one of the sashes, the cam edges 10 of the locking pawl will engage the pin 7 and in so doing will cause the rear end of the pawl to move upwardly. It therefore follows that the pin 6 moves 95 upwardly in the inclined slot and the thrust exerted on the pawl by the downward movement of the sash causes this pin to engage the upper inclined edges of the slots which function as cams and compel the pawl to move toward the sash and obtain a tighter and more effective grip. 100

At this point I wish to again call attention to the fact that with this arrangement and construction, the necessity of removing the attaching member and moving it closer to the upper sash as was found necessary 110 with my patented device, due to the fact that the pawl did not effectively engage this sash when the latter becomes worn enough to increase the space between itself and the attaching member, is overcome. In other 115 words, the locking pawl of the present device will always move to properly engage the sash with which it co-acts, regardless of whether or not this sash becomes spaced slightly further away from the attaching 120 member than when the device was originally attached to the window.

From the foregoing description, it will be seen that I have devised an extremely advantageous sash holder which is a decided 125 improvement over my patented device and all other prior art devices with which I am familiar, since it permits independent longitudinal movement of the locking pawl, which is necessary under some circumstances. 130

I again wish to emphasize the fact that such movement of the locking pawl causes the same to more effectively grip the sash in case either of them is moved to open position. The device is automatic in operation and the locking pawl can be easily swung out of operative position to permit the sash to be easily and readily moved to open position. Furthermore, the construction and arrangement which I employ is extremely simple and inexpensive and is such that the parts may be readily disconnected for replacement and repairing.

A careful consideration of the foregoing taken in connection with the accompanying drawings will enable persons skilled in the art to which this invention relates to obtain a clear understanding of the same, therefore, a more lengthy description of the use and advantages of the device is thought unnecessary.

Since probably the best results may be obtained with the construction and arrangement disclosed, I take this construction and arrangement as the preferred embodiment of my invention. However, I wish it to be understood that various minor changes in the shape, size, and arrangement of parts may be resorted to without departing from the spirit of the invention or the scope of the subjoined claims.

I claim:

1. A window lock comprising an attaching member having a pin constituting a fulcrum, a sash engaging pawl connected with said member and capable of longitudinal movement with respect thereto, and cam co-acting means between the pawl and fulcrum for causing said longitudinal movement.

2. A sash holder comprising an attaching member having a fulcrum, and a locking pawl movable longitudinally with respect to said attaching member and being provided with a portion for engaging one of the sashes and further provided with an arm pivoted to said member, the lower edge of said arm being curved to provide a cam surface which bears on said fulcrum.

3. A sash holder comprising an apertured attaching base provided with spaced guide walls having inclined elongated slots formed therein at points opposite each other, said slots being inclined in the same direction, a locking pawl provided with means for frictionally contacting the sash and also provided with arms extending between said walls, a pivot and connecting pin passing through said slots and arms, being movable in said slots to permit said pawl to move longitudinally with respect to the base, and co-acting cam means between the latter and

pawl for causing such movement of the latter.

4. A sash holder comprising an apertured channel-shaped attaching base, the side walls of which are provided with opposed diagonally inclined guide slots, a pin extending horizontally through said side walls, a retaining pawl having a portion for engaging the sash and a pair of spaced apertured arms arranged between the side walls of said base, the lower edges of these arms normally resting on said pin, providing cam means for moving said pawl longitudinally with respect to the base, a pivot pin extending through the aforesaid slots and apertures in said arms, and a spring coiled around said pivot pin having one of its ends anchored on one of said arms, its opposite end resting against said first pin.

5. The structure set forth in claim 2, said fulcrum pin being rotatable, whereby its points of contact with the arm will change constantly and thus increase its length of life.

6. A window locking device comprising an attaching member provided with a horizontally disposed pin constituting a fulcrum, a sash engaging pawl engageable with said fulcrum when moved downwardly by one of the sashes, and a connection between the member and pawl including cam co-acting means for moving the pawl longitudinally with respect to the member when the pawl is brought to bear on said fulcrum.

7. A window locking device comprising an attaching member formed with a cam slot, a sash engaging pawl, a connecting pin carried thereby and slidable in said slot, said pin normally resting in the lower end of the slot, and cam co-acting means between the member and pawl for moving the pin upwardly in said slot.

8. A window locking device comprising a stationary attaching member provided with inclined slots and provided in advance of and beneath these slots with a fulcrum pin, a pawl associated with said member and having a connecting pin disposed in said slot, said pawl being also provided with cam means bearing on said fulcrum pin.

9. A window locking device including a channel shaped attaching member having inclined slots formed in its opposite vertical walls at oppositely disposed points, being also provided in advance of these slots and just below them with a horizontally disposed pin constituting a fulcrum.

In testimony whereof I have hereunto set my hand.

JOSEPH J. PRUELL.
